UNITED STATES PATENT OFFICE.

BENJIMAN N. BERMAN AND ABRAHAM HARRIS, OF PHILADELPHIA,
PENNSYLVANIA.

BUNCHING-MACHINE FOR MAKING CIGARS.

No. 813,766.

Specification of Letters Patent.

Patented Feb. 27, 1906.

Application filed April 28, 1905. Serial No. 257,842.

To all whom it may concern:

Be it known that we, BENJIMAN N. BERMAN and ABRAHAM HARRIS, of the city and county of Philadelphia, State of Pennsylvania, have invented an Improvement in Bunching-Machines for Making Cigars, of which the following is a specification.

Our invention has reference to bunching-machines for making cigars; and it consists of certain improvements which are fully set forth in the following specification and shown in the accompanying drawings, which form a part thereof.

The object of our invention is to provide a suitable construction of bunching-machine adapted to be operated by hand, whereby the operator may bunch the tobacco preliminary to being placed in the wrapper and by which the operation may be more satisfactorily performed to insure the requisite shape required without danger of making the filler too dense for proper smoking.

Our object is also to provide the machine with adjustable capacity whereby different-shaped fillers may be made as desired.

Our invention consists of a die of elastic or yielding material combined with an apron above it and in which the tobacco filler is placed and a swinging arm having a roller for operating upon the apron and adapted to swing closely over the die; also, in having the swinging arm pivoted and formed with an adjustable end by which the roller may be supported at various angles to the surface of the die; further, in having the axis of the roller adjustable vertically to vary the position vertically relatively to the upper surface of the die.

Our invention also comprehends details of construction, which, together with the features above specified, will be better understood by reference to the drawings, in which—

Figure 1 is a plan view of a bunching-machine embodying our improvements. Fig. 2 is a sectional elevation of same on line 2 of Fig. 1. Fig. 3 is a section of Fig. 1 on line 3, and Fig. 4 is an end view of the roller-shaft and supporting-arm with part in section.

A is the table or bench, only a portion of which is shown. Usually each machine comprises a small table with the appliances here shown; but it is evident that a series of these

appliances may be arranged side by side upon a long bench.

B is a segmental die, preferably of rubber or other yielding or elastic material, and has the recess B' near the forward end. It is secured to the table A by the end clamps C C. The rear clamp C is extended to form a groove C' to receive the cigar-filler after the same has been rolled and compressed.

D is the apron and may be made of oil-cloth, leather, &c., and has its ends secured to the clamp-plates C C by the clamping-bars c c, the length of the apron being considerably longer than the length of the die B, whereby it may be formed into a reverse loop to pass about the tobacco filler S and also the roller E.

The roller E is loosely journaled on the shaft F, terminating in the ball-handle F' at its free end and having the other end adjustably clamped to a swinging arm of special construction. The swinging arm J is journaled upon the downwardly-extending pin L, secured to the bottom of the table or bench A, and is supported upon antifriction-balls N, carried upon the head M. To the free end of the arm J is hinged at K the bell-crank arm H H', the part H' being adjustable between the adjusting-screws I I on the arm J and the part H being extended upward through a slot P in the table and forming a support for the shaft F of the roller E. This shaft extends through a vertical slot h in the part H and is adjustable vertically therein, being clamped in place by the nut G. The curvature of the slot P and die B are made with the shaft L at the center, as will be obvious from Fig. 1.

We do not confine ourselves to any form of adjustment between the arm H and the swinging arm J, that shown being one form which we have found well suited to the purposes of our invention.

The roller E is preferably made tapering, so that the outer end will have a surface speed commensurate with the increased length of the apron at the outer or right-hand edge over the length at the other or left-hand edge. This also, with the arm H arranged vertical, gives an obliquity to the roller, as shown in Fig. 2, to form a tapering space between it and the die which corresponds to the taper to be given to the filler. This obliquity of the

roller may be increased or decreased by adjusting the arm H, which may be accomplished by the screws I I.

The operation will now be understood. 5 The roller E is moved to the right, Fig. 3, as far as it will go. The tobacco filler is then placed upon the apron, crowding it down into the groove or recess B'. The roller is then moved over the die, which action folds the 10 apron over the filler S, as shown in Fig. 3. By continuing the roller as far to the left in Fig. 3 as it will go the compressed filler is rolled into the receiver C'. The elasticity of the rubber die B forms a yielding bed upon 15 which the rolling of the filler is done, and should the filler tend to be rolled too hard the die gives and prevents the compression from being too tightly done. These features enable an operator to perform good work all 20 the time and with less care and risk.

If desired, the head M may be adjusted vertically by the set-screw m; but ordinarily the adjustment secured at h in the arm H will be found amply sufficient.

25 We do not limit ourselves to the details, as these may be varied without departing from the spirit of the invention.

Having now described our invention, what we claim as new, and desire to secure by Letters Patent, is—

30 1. In a bunching-machine, the combination of a die of yielding material, a loose apron having its ends secured adjacent to the ends of the die, a swinging arm pivoted to a support to one side of the die and having at 35 its free end an adjustable part hinged to the arm on an axis in the plane of movement of the swinging arm and provided with a laterally-extending shaft, and a roller journaled 40 upon said shaft and arranged between the apron and die, the construction being such that the vertical obliquity of the roller may be varied through the adjustable part on the end of the pivoted swinging arm.

45 2. In a bunching-machine, the combination of a die, a loose apron having its ends secured adjacent to the ends of the die, a pivoted swinging arm pivoted below the die and having an upwardly-arranged arm extending above the die and provided with a slot, a laterally-extending and overhanging transverse shaft arranged above the die and adjustably clamped in the slot of the upright arm to provide vertical adjustment, and a 55 roller carried by the said shaft and arranged between the apron and the die.

3. In a bunching-machine, the combination of a die, a loose apron having its ends secured adjacent to the ends of the die, a pivoted swinging arm pivoted to the table below 60 the die and having an upwardly-extending arm extending above the die, a transverse shaft arranged above the die adjustably connected to the upright arm with provision for

vertical adjustment, a roller carried by the 65 said shaft and arranged between the apron and the die, and pivoted means for adjusting the vertical obliquity of the roller relatively to the die and to the pivoted swinging arm.

4. In a bunching-machine, the combination of a die of yielding material, a loose apron having its ends secured adjacent to the ends of the die, a swinging arm consisting of a part swinging upon a fixed vertical axis and a second or upright part adjustably pivoted 70 to the free end of the first-mentioned part on a transverse axis, means to adjust the second part in position upon the swinging arm, and a roller carried by the second part of the arm and arranged between the apron and die. 75

5. A bunching-machine of the character described having a die over which the bunch is rolled in a compressed form made throughout its entire length and width of rubber and having near one end a transverse depression, 80 provided with an elastic shoulder at the juncture of said depression and the upper surface of the die over and against which the bunch may be forced and compressed under the elasticity of the said shoulder, and metallic 85 clamping devices C C extending over the extreme ends and upper edges of the elastic die for holding it in position, and a loose apron having its ends secured to the said metallic clamps and its intermediate portion loosely 90 supported over the die.

6. In a bunching-machine, the combination of a table, a die supported upon the table, a loose apron having its ends secured adjacent to the ends of the die, a swinging arm pivoted to a support at one side of the die and below the table and having an upright part extending upward above the table and to one side of the die, and a roller carried by the upright part and arranged between 100 the apron and die for moving the apron and adjustably attached to vary its vertical obliquity relatively to the die.

7. In a bunching-machine the combination of a die having a groove at one end, a 105 loose apron having its ends secured adjacent to the ends of the die, a swinging arm consisting of a part swinging upon a fixed vertical axis and a second or upright part adjustably pivoted to the free end of the first-mentioned part on a transverse axis, means to adjust the second part in position upon the swinging arm, and a roller carried by the second part of the arm and arranged between 110 the apron and die.

8. In a bunching-machine, the combination of the table, a die having a groove at one end resting upon the table, a loose apron having its ends secured adjacent to the ends of the die, a swinging arm pivoted to a support 115 at one side of the die and upon the under side of the table, an upright part adjustably connected with the free end of the arm and ex- 120

tending to a point above the table, a roller carried by the adjustable upright part of the arm and arranged between the apron and die, and adjustable means for connecting the 5 roller to the upper end of the upright arm whereby it may be adjusted to or from the die as well as have its obliquity varied.

9. In a bunching-machine, the combination of a die having a groove at one end, a 10 loose apron having its ends secured adjacent to the ends of the die, a pivoted swinging arm, a shaft adjustably clamped upon the pivoted swinging arm whereby it is adjustable obliquely to or from the die in a vertical 15 direction, and a roller carried by the shaft and arranged between the apron and die.

10. In a bunching-machine, the combination of a die, a loose apron having its ends secured adjacent to the ends of the die, a 20 pivoted swinging arm pivoted to a support at the side of the die, an upright part pivoted to the end of the swinging arm and adjustable laterally to or from the die, and a tapering roller carried by the upright part and arranged between the 25 apron and die.

11. In a bunching-machine, the combination of the die, the swinging arm J having the bell-crank portion H H' adjustably pivoted at K and held in adjusted position by adjusting-screws I I, the shaft F secured to the part 30

H of the bell-crank portion, a roller E journaled upon the shaft F, and loose apron D extending over the roller and die and having its ends secured adjacent to the ends of the die.

12. A bunching-machine having a die made of one continuous piece of elastic or yielding material in which the transverse groove B' is formed, combined with metallic clamping devices independent of the die and 40 at each end for directly holding the die in position, an apron having its ends clamped to the clamping devices, and a swinging arm having a laterally-extending portion arranged between the apron and die.

13. In a bunching-machine, a die upon which the tobacco fillers are rolled consisting of a thick flat block of rubber segmental in plan and having a transverse groove formed in the upper surface of the body of the rubber near one end the said die being elastic throughout its entire length.

In testimony of which invention we hereunto set our hands.
